COMPRESSED AIR COOLANT CIRCULATORY
PUMP

John De Witt Gray and Wilfred S. Stone, Chicago, Ill., assignors to John De Witt Gray and Lloyd L. Miller, Chicago, Ill., partners doing business as Gray-Miller Co.

Application June 26, 1943, Serial No. 492,368

13 Claims. (Cl. 103—238)

This invention relates to coolant circulatory systems of the type described in the co-pending application Serial No. 436,082 of John De Witt Gray and Edward C. Rothacker. More particularly, this invention relates to such a coolant circulatory system driven by compressed air.

Heretofore, coolant pumps have commonly been driven by an electric motor. Electricity is always available in places employing machine tools. Electrically driven pumps, however, are particularly subject to wear. Whether the pump is of the gear or centrifugal type, metal chips will work their way down from the collection pans beneath the machine tools into the coolant reservoir and thence into the pumps. Moreover, the coolant acquires considerable heat and very quickly raises the temperature of the pump and motor to a point where it loses efficiency.

Broadly, the object of this invention is to provide a coolant circulatory system or pump driven by air pressure. In a large percentage of the machine shops or other places where machine tools are used, compressed air is as available as electricity. Compressed air is commonly used to blow chips from the work during machining operations.

Applicant uses compressed air for forcing fluid from a substantially gas-tight tank much in the way that air is now used to assist in evacuating a beer barrel. Unlike the problem of evacuating a plurality of beer barrels in succession, a coolant circulatory system functions by means of returning the fluid or coolant from a collection pan beneath the machine tool by gravity to the original container or pumping means. In order to obtain continuous operation, the fluid must be reintroduced to the original container during a period when there is no compressed air therein. This necessitates the employment of more than one container. After the compressed air has emptied one container, it must almost instantaneously commence to empty a second container because the machine tool may be working on metal where lubrication and cooling must be substantially continuous.

With the foregoing considerations in mind, one specific object of this invention is to employ a double tank arrangement wherein the air pressure will evacuate one tank while the other tank is not under pressure but is receiving by gravity fluid from the coolant collection pan. In connection with this object, applicant provides automatic means for alternately emptying one tank and then the other.

Another specific object of this invention is to

provide means for transferring the application of air pressure from one tank to the other tank almost instantaneously so that a single delivery line from the unit will result in a steady flow at the nozzle of the circulatory system. In this connection, applicant uses a spring toggle arrangement controlled by a float in one of the chambers. A lever train controlling all of the valves for introducing compressed air, for introducing by gravity coolant from the collection pans, and for alternately opening and closing the coolant delivery lines from the two chambers is controlled by the action of a spring which is free to snap into either of two positions depending upon the position of the float in one of the chambers.

The invention includes many structural features. It is desirable that coolant pumps be inexpensively made. Toward that end applicant employs a small round container of standard construction positionable in a larger container, likewise round and of standard construction. The smaller container is mounted removably on the under side of a lid for the large container. Mounted on the upper side of the lid and straddling the side wall of the smaller container is the valve assembly which is built into a single casting. All of the movable parts of the device are mounted on the lid, with the result that the device may be readily disassembled. The opening and closing of the valves is controlled entirely by a float, which gives a positive action although not requiring finely machined bearings and journals in the linkage connections.

These and such other objects as may herein-after appear are attained in the embodiment of the invention shown in the accompanying drawings wherein:

Figure 1 is a side view in section of the device; Figure 2 is a plan view taken on the line 2—2

40 of Figure 1; and

Figure 3 is a plan view taken on the line 3—3 of Figure 1.

Continuing to follow the drawings, the numeral 10 identifies a large container or chamber having a bottom 12 and a strong lid 14. A gas-tight connection between the container 10 and the lid 14 may be obtained by employing a gasket 16 and suitable fastening means such as the nuts and bolts 18. Suspended from the lid 14 is a second container 20 having a bottom 22 and using the lid 14 as a top closure member. Here again a gas-tight connection is obtained by means of a gasket 24 and suitable fastening means 26.

Mounted on the top of the lid 14 is a casting 28 having a coolant collection bowl 30 and

through its base substantially horizontal or parallel to the lid 14 a cylindrical chamber 32 open at one end. Two passageways or delivery ports 34 and 36 in the bottom of the bowl 30 open directly into the cylindrical chamber 32 and extending through the lower side wall of the cylindrical chamber 32 as passages 38 and 40, these passages being defined by integral depending collars 42 and 44. These collars 42 and 44 are externally threaded at 46.

From the cylindrical chamber 32, downwardly directed, are passages 48 and 50 through which compressed air may be introduced to the containers 10 and 20. These passageways 48 and 50 in their lower reaches are defined by collars 52 and 54 formed integrally with the casting 28 and having their lower ends externally threaded.

Two other openings from the casting 28 through the lid 14 exist. These passageways are numbered 56 and 58 in Figure 3, and, returning to Figure 1, have depending collars 57 and 59 formed integrally with the casting 28 similar to the collars 52 and 54. These collars 57 and 59 have their lower ends internally threaded.

The six depending collars 42, 44, 52, 54, 57 and 59 constitute the means for assembling the casting 28 in an air-tight relationship to the lid 14. A gasket such as 60 is positioned over each collar and a nut such as 62 is tightened over each of the collars after the casting 28 has been seated in six holes cut in the lid 14 in registry with the depending collars.

Two delivery tubes 62 and 64 having their upper ends threaded are screwed into the internal threads in the bases of the depending collars 57 and 59.

Referring now to Figure 3, the upper end of the delivery passageways 56 and 58 turn at right angles and leave the casting horizontally by the passageways 66 and 68 into pipes 70 and 72. The two pipes or delivery lines join to form a single delivery line 74, there being a check valve 76 in the pipe 70 and a similar check valve 78 in the pipe 72.

Leading horizontally into the cylindrical chamber 32, referring to Figure 3, is a passageway 80 for introducing compressed air from the line 82. Also leading into cylindrical chamber 32 are horizontal air vents 84 and 86. Disposed in the cylindrical chamber 32 is a piston 88 which has its cylindrical surface cut back between end portions 90 and 92 to form between partitions 94 and 96 with the walls of the cylindrical chamber 32 a plurality of movable chambers which bear a fixed relationship to each other and which are in communication with various passageways leading from the cylindrical chamber 32, depending upon the position of the piston 88. Threaded into the end portion 92 of the piston 88 is a rod or link 98 which passes through an opening in an end plate 99 which closes the open end of the cylindrical chamber 32 and which is held in position by cap screws such as 100.

Referring now to Figure 1, the outer end of the rod 98 is bent and rides in a slot 102 of a bell crank lever 104 pivotally mounted at 106 on an extension 108 of the casting 28. At its outer side, the bell crank lever 104 carries a closed track 110 in which rides the turned end 112 of a link 114 which passes through an opening 116 in the lid 14. In order to hold the link 114 closely to vertical movements, or a movement at right angles to the lid 14, a reinforcing member 118 is suitably fastened to the bottom of the lid 14 and there may be packing 120 between the reinforce-

ing member and the link 114 held in position by a cap screw 122.

The lower end of the link 114 rides in a closed track 126 in an arm 128 pivoted at 130 to a depending support member 132. The support member 132 is a casting which is held in assembled relationship with the lid 14 by means of an opening 134 in the support member 132 fitting over the enlarged collar 44 and a nut 136 which is drawn up on the external threads on the collar 44.

Pivotedly connected to the arm 128 at 138 is another link 140 having a closed track 142 in its lower end in which track rides a stud 144 which is formed integrally with a T-shaped casting 146. The T-shaped casting 146 is pivotally mounted at 148 on an extension 150 of the casting 132 inwardly directed with respect to the inside wall of the container 20. The T-shaped casting 146 therefore can move in an arc around the center 148 from the continuous line position illustrated to the broken line position 152. As may be seen by comparing Figure 2 with Figure 1, the depending link 140 is mounted behind the T-shaped casting 146, the relationship being maintained by a nut 153 which loosely engages the side walls of the link 140.

Projecting forwardly of the T-shaped casting 146 as viewed in Figure 1 are two lugs 154 and 156 mounted at the outer ends of the cross member of the T respectively. Between these lugs 154 and 156 is positioned the arm 158 of a float 160 which arm is pivotally mounted at 162 on an outwardly directed extension 164 of the support member 132. Referring to Figure 2, it will be noted that the arm 158, in order to move vertically and at all times engage either one or the other of the lugs 154 and 156, must be spaced from the support member 132 and this is effected by means of the spacer member 166 which is fastened to the portion 164 by any suitable means. Connecting the spacer member 166 to the intersection point 162 of the T-shaped casting is a spring 167. Referring to Figure 1, it is evident that the T-shaped casting 146 will always assume one of two positions depending upon the relationship of the spring 167 to the pivotal point 148. If the spring 167 is above the pivotal point 148, the spring 167 will snap the T-shaped casting 146 into position 152, and if the spring 167 is below the pivotal point 148, it will snap the T-shaped member 146 into the continuous line position shown.

The downwardly displaced portion 169 in the arm 158 is to assure noninterference between the bulb 160 in its uppermost position and the link 114.

Continuing to refer to Figure 1, the line 74 is normally flexible and terminates in the nozzle 168 which will be directed upon some machine tool such as 170. Discharged fluid will be collected in a pan 172 from which it will flow by gravity down the line 174 through a lid 176 into the collection bowl 30. An air vent 178 is provided in the lid 176 of the collection bowl 30 which is tightly fastened thereto by cap screws such as 180 for reasons hereinafter explained. A sieve 182 removably suspended from the under side of the lid 176 will collect any large particles that may pass down the line 174.

From a construction standpoint, the control mechanism functioning in the container 20 possesses the desirable characteristics of positive action, long life, and a minimum labor requirement in fitting and aligning the operable parts.

None of the journals or bearings of the float and linkage mechanism are machined, with the exception of the link 114 and the opening through the reinforcing member 118. Gaskets are relied upon to obtain the necessary seal between the inside of the containers and the outside.

Operation

When the device is first made ready for use, the operable parts will be in the various positions indicated by the continuous lines shown in Figure 1. The float 160 will be near the bottom of the container 20 because there is no fluid in the system. The intake lines 82 and 80 for the compressed air may be connected to a source of compressed air but a control valve 184 will be maintained in closed position. The collection bowl 30 may be connected by a line such as 174 to a collection bowl 30 by permitting it to flow down the line 174 or the machine may be filled by pouring fluid directly into the collection bowl 30 through the opening 175. The coolant will flow down the passageways 36 and 40 into the container 20 and the float will begin to rise. When the float reaches the dotted line position 188, the arm 158 will engage the lug 154 of the T-shaped casting 146. As the float 160 continues to rise, the T-shaped casting 146 will move counter-clockwise around the center 148. In so doing it is obliged to expand the spring 167. The movement of the T-shaped casting 146 does not raise the link 140 because the stud 144 moves freely in the closed track 142, although the stud does swing the link 140 inwardly of the container 20 around the center 138. When the float 160 reaches position 190, the stud 144, the point 148 and the point 162 will all be in alignment and the spring 167 will be stretched to the maximum extent permitted by the assembly. As the float 160 continues to rise under the influence of the incoming coolant, the spring 167 will assume control of the movement of the T-shaped casting 146 and snap it into position 152. In so doing the link 140 will be snapped upwardly and the bell crank lever 104 will be snapped into position 192. The float 160 may continue to rise a short distance, but when the bell crank lever moves into position 192, the influx of coolant from the collection bowl 30 ceases and the passageway 50 which had been in communication with the vent 86 comes into communication with the compressed air intake line 80.

When this condition occurs, the valve 184, see Figure 3, is opened by hand and compressed air now passes down the passageway 80 through the chamber established by the partitions 94 and 96 of the piston 88, down the passageway 50, see Figure 1, into the container 20. The air pressure established in the container 20 forces the fluid out through the delivery line 64 and ultimately to the tool 170. The rate of flow will depend upon many factors including the relationship of the surface area of the fluid to the inside diameter of the delivery line 64 and to the control nozzle 168. The most important control in the rate of flow will be the air pressure in the tank 20. It is necessary to be able to control the air pressure in order to adjust it for coolants of different viscosities and to compensate for changes in atmospheric pressures. This is done by means of a reducing valve 194 in advance of a gauge 196, see Figure 3. These devices are conventional but perform an important function in connection with the operation of this device as a whole.

It is also necessary for the flow of coolant to be continuous at a substantially constant pressure regardless of which tank, 10 or 20, is being emptied without necessitating adjustment of the air pressure. For this reason the cross sectional area of the inside of the tank 10 is exactly twice the cross section of the outside dimensions of the tank 20. In other words, the surface of oil engaged by the compressed air in the tank 10 is exactly equal in area to the surface of oil engaged by the compressed air in the tank 20.

Resuming the description of the operation, the coolant is now flowing from the container 20 to the nozzle 168 and the container 10 is being filled through the passageways 34 and 38, there being a vent to atmosphere through the passageway 48, cylindrical chamber 32 and air vent 84. The chamber 10 will fill comparatively quickly due to the size of the openings 34 and 38 and in starting the device for the first time, the coolant should be led into the collection bowl slowly so that the container 10 does not flood. If this should happen, the fluid will flow up the passageway 48 and out through the air vent 84. Moreover, when the piston is again thrown to the position shown in Figure 1, the inflow of compressed air will cause quite a lot of trouble. The lid 176 is securely fastened to the top of the collection bowl 30 because when the position of the valve assembly is reversed, the air will vent to a certain extent up the passageways 34 or 36 and would splash out coolant in the collection bowl 30 but for the tightly fastened lid 176 with its small vent 178.

As the float 160 descends with the fluid level in the container 20, it ultimately reaches a position where it permits the spring 164 to throw the T-shaped casting from dotted line position 152 into the continuous line position shown. When this occurs, the bell crank lever 104 is snapped into the continuous line position shown and the compressed air from the line 80 now descends the passageway 48 and commences to evacuate the coolant from the container 10 out the delivery pipe 62. It is evident, therefore, that the device will automatically in response to movement of the float evacuate one container and then the other and will operate continuously so long as the system contains an adequate supply of fluid and an adequate supply of compressed air.

Attention is invited to the fact that the delivery lines 66 and 68, see Figure 3, each contain check valves to prevent the device from pumping fluid from one container into the other container.

These valves are conventional and are shown schematically only.

Having thus described our invention, what we claim as new and desire to claim by United States Letters Patent is:

1. A compressed air pump comprising means for collecting fluid not under pressure, a container, a communicating means between said collecting means and said container, means for withdrawing a portion of said fluid from said container and having a delivery means, and means operated by air pressure for forcing the withdrawn fluid through said delivery means, a common valve means in said communicating means and said delivery means, and a float means in said container and connected to said common valve means.
2. A compressed air pump comprising means for collecting fluid not under pressure, a substantially gas-tight chamber, means including a communicating means between said collecting

means and said chamber for introducing a portion of said fluid into said chamber, a delivery means having an outlet in the lower part of said chamber, and a common valve means in said communicating means and said delivery means operable when the aforesaid introducing means is not functioning for introducing compressed air to the chamber whereby fluid flows into the outlet.

3. A compressed air pump comprising means for collecting fluid not under pressure, a substantially gas-tight chamber including a communicating means between said connecting means and said chamber, valve means in said communicating means for introducing a portion of said fluid into said chamber, a delivery means having an outlet in the lower part of said chamber, a second valve means in said delivery means and operable when the aforesaid introducing means is not functioning for introducing compressed air to the chamber whereby fluid flows into the outlet, a second substantially gas-tight chamber having a similar set of valves, and means for functioning the valves for the two chambers in opposed sequence whereby when one chamber is being emptied of fluid by the compressed air, the other chamber is being filled from the collection means.

4. A compressed air pump comprising means for collecting fluid not under pressure, a pair of substantially gas-tight containers, and two-position valve means capable in one position of filling one container with fluid from the collecting means while concurrently connecting the other container to a source of compressed air and capable in its second position of filling the other container with fluid from the collecting means while concurrently connecting the first container to a source of compressed air, and means responsive to the fluid level in one of the containers for fully actuating said two-position valve into either of its positions.

5. A compressed air pump comprising a pair of substantially gas-tight containers, common valve means for controlling the introducing of fluid by gravity to one container and compressed air to the other container, means for moving said valve means to control the reversing of said air and fluid connections whereby the compressed air is introduced to the first container, fluid is introduced to the second container, and float means in the first container for functioning said reversing means when the fluid level in the first container reaches a predetermined level, and means responsive to a selected position of said float means for fully actuating said moving means irrespective of further movement of the float means in the same direction.

6. A compressed air pump comprising means for collecting fluid not under pressure, a pair of substantially gas-tight containers having equal horizontal cross sectional areas, valve means for alternately connecting the collecting means to one container and a source of compressed air to the other container, a float in one container functioning said valve means when in an upper or lower position, and means responsive to a selected position of said float means for fully actuating said moving means irrespective of further movement of the float means in the same direction.

7. A compressed air pump comprising means for collecting fluid not under pressure, a pair of substantially gas-tight containers, a two-position valve capable in one position of connecting the first container to the collection means and

the second container to a source of compressed air and capable in the second position of reversing the connections so that the second container is connected with the fluid collection means and

5 the first container is connected to the source of compressed air, and means for holding said valve in the first position until the first container is comparatively full of fluid and of automatically shifting the valve to the second position when the first container becomes comparatively empty.

8. A compressed air pump comprising means for collecting fluid not under pressure, a pair of substantially gas-tight containers, a two-position valve capable in one position of connecting the first container to the collection means and the second container to a source of compressed air and capable in the second position of reversing the connections so that the second container is connected with the fluid collection means and

15 the first container is connected to the source of compressed air, and means for holding said valve in the first position until the first container is comparatively full of fluid and of automatically shifting the valve to the second position when the first container becomes comparatively empty.

9. A compressed air pump comprising means for collecting fluid not under pressure, a pair of substantially gas-tight containers, a two-position valve capable in one position of connecting the

30 first container to the collection means and the second container to a source of compressed air and capable in the second position of reversing the connections so that the second container is connected with the fluid collection means and

35 the first container is connected to the source of compressed air, and a float in the first container so connected to the two-position valve that when the float is in a low position it will hold the valve in its first position and when the float is raised

40 it will hold the valve in its second position.

10. A compressed air pump comprising means for collecting fluid not under pressure, a pair of substantially gas-tight containers, a two-position valve capable in the first position of connecting the first container to the collection means and the second container to a source of compressed air and in the second position of reversing the connection to connect the second container to the collection means and the first container to the compressed air, and means responsive to the fluid level in the first container for practically instantaneously snapping said two-position valve from one position to the other.

11. A compressed air pump comprising means for collecting fluid not under pressure, a pair of substantially gas-tight containers, a two-position valve capable in the first position of connecting the first container to the collection means and the second container to a source of compressed air and in the second position of reversing the connection to connect the second container to the collection means and the first container to the compressed air, and means responsive to the fluid level in the first container for

60 practically instantaneously snapping said two-position valve from one position to the other, said means comprising a spring operable upon the two-position valve only when it has passed a dead center point after which it is free to contract.

12. A compressed air pump comprising a pair of substantially gas-tight containers, a two-position valve capable in one position of introducing compressed air to one container and fluid to the other container and in the second position of re-

versing the air and fluid connections to the containers, a float in one container, a linkage connecting the float to the two-position valve, and means for moving the valve from one position to the other position when the float approaches its lowermost position or its uppermost position in one of the containers.

13. A compressed air pump comprising one substantially gas-tight container positioned inside a larger substantially gas-tight container, 10 the cross sectional horizontal areas of said con-

5 tainers being substantially equal, a two-position valve capable of introducing fluid to one container and compressed air to the other container when in its first position and of reversing the air and gas connections when in its second position, and float means within one container for snapping the valve from the first position to the second position in order to produce a continuous flow of fluid out a delivery line.

JOHN DE WITT GRAY.
WILFRED S. STONE.
